UNITED STATES PATENT OFFICE.

CHARLES H. CALKINS, OF LUDLOW, MASSACHUSETTS, ASSIGNOR TO BAUSH MACHINE TOOL COMPANY, A CORPORATION OF MASSACHUSETTS.

RAILWAY-CAR DRIVING MECHANISM.

1,240,419.

Specification of Letters Patent. Patented Sept. 18, 1917.

Application filed March 17, 1916. Serial No. 84,855.

To all whom it may concern:

Be it known that I, CHARLES H. CALKINS, a citizen of the United States, residing in Ludlow, Massachusetts, have invented certain new and useful Improvements in Railway-Car Driving Mechanism, of which the following is a specification.

This invention aims to provide a new driving mechanism for railway cars whereby a great reduction of speed between the motor and the driven wheels can be secured in a small space with very few parts, with less noise than previous driving mechanisms make and with great efficiency and whereby 15 also a high speed and comparatively light motor may be used. Other points of advantage are referred to hereinafter.

The accompanying drawings illustrate an embodiment of the invention.

20 Figure 1 is a plan of the principal parts of a railway car truck with the improved driving mechanism applied thereto;

Fig. 2 is a side elevation of the same partly in section as indicated by the line 25 2-2 of Fig. 1;

Fig. 3 is a side elevation of one of the axles showing the driving gear in section;

Fig. 4 is a sectional view approximately on the line 4-4 of Fig. 3.

30 Referring now to the embodiment of the invention illustrated, this represents a single truck street railway car of a known type. The wheels A are driven by shafts B which at their outer ends support journal boxes C which carry side rails D. The weight of the car comes directly on longitudinal bars E which are supported through intermediate leaf springs F upon the ends of the rails D and through intermediate coiled springs G upon flanges on the bottom of the journal boxes; the bars E being stiffened by truss rods H, H' connected at their ends to the bars E and connected thereto at intermediate 40 points by rods J which pass through the 45 coiled springs.

The wheel shafts are each in two sections B and B' and are extended through a tubular axle K which is transversely divided and carried on bearings on the wheel shaft 50 as hereinafter described, so that each wheel shaft carries the weight of the hollow axle and rotates within the same. The hollow axle may be braced by diagonal rods such as L and M, Fig. 3, integral therewith or fastened thereto in any suitable way. Each

wheel A carries an inside flange N for engagement by a brake-shoe.

The motor O is preferably of the electric type, but not necessarily. It is supported by flanges P of its casing resting on supporting bars Q which at their ends are supported on the hollow axles K. This motor is arranged with its shaft R extending longitudinally of the car. The opposite ends of the motor shaft are connected to a flexible shaft comprising an intermediate portion S connected by universal joints T to the driving gears.

Each axle has at its center a gear casing U divided transversely as shown for convenience in assembling and shaped to inclose at 70 the top a worm V on a shaft W which is connected to the adjacent universal joint T. Driven by the worm V is a worm gear X, the hub Y of which forms bearings for the two separate sections B, B' of the wheel shaft, 75 the hub Y being free to rotate about the shaft sections. Ball bearings Z are interposed between the hub Y and the sections of the tubular axle K, so that the hub is free to rotate therein. Carried within the hub Y of 80 the worm gear are spiral gears a mounted on radial spindles b so as to be carried bodily around with the worm gear X. On opposite sides of each spiral gear a and in engagement therewith are spiral gears c and 85 d. The gear c is in turn engaged with a spiral gear e on one of the shaft sections B; and the gear d is engaged with a corresponding spiral gear f on the opposite shaft section B'. Each shaft section B is squared or 90 otherwise splined into its gear, e and f respectively, thus providing a semi-floating rear axle construction. The shaft sections B, B' are permanently attached to the wheels A. Therefore, by jacking up the car, 95 any wheel A with its shaft section can be withdrawn endwise out of the axle without disturbing the mechanism. The spiral differential gearing shown is of a known type, such as is described more fully for example 100 in Patent No. 1,090,082 of March 10, 1914 to Muehl. The invention may be used, however, with any usual or suitable style of spiral differential gearing, or in fact with any ordinary spur or bevel differential gearing, 105 or without differential. In the last case a single integral driving shaft would be used for both traction wheels of a pair and the worm gear X would be mounted directly on the driving shaft. I have used the term 110

wheel shaft to include either an unbroken shaft for a pair of wheels or a shaft in two sections, one for each wheel. The spiral differential gearing is preferred, however, for 5 communicating the motion of the worm gear X to the driven shaft sections because it has not only the advantage of permitting the opposite traction wheels to advance at different 10 rates of speed as the car goes around a curve, but will drive wheels at both sides at all times, so that where one rail may be slippery the wheel will not spin around while the opposite wheel remains unmoved.

The worm V and gear X by which the 15 wheel shafts are driven permits of a great reduction of speed in the smallest possible space. For example, with the proportions illustrated a reduction of six to one may be effected, giving a speed of thirty miles per 20 hour to the car with a motor making two thousand revolutions per minute. With the bevel or spur gears ordinarily used for driving street cars the designer has generally to choose between two difficulties. In one case 25 the pinion must be too small or the gear too large to go in the permitted space; in the other case two sets of gears must be used with an increased complication and cost. With worm gearing arranged as shown a 30 great reduction may be obtained at once in a small space and with only two parts. The worm drive has a great advantage over the ordinary spur or driving gear used on street cars in the matter of noise. The worm drive 35 is practically silent and does not become noisy with wear or with increased speed. In the ordinary gearing used on street cars the noise is always great and becomes greater as the gears wear and an especially great 40 nuisance at high speeds. Where a differential is introduced between the worm gear and the shaft sections the car can go around curves more smoothly and without the grinding of the wheels on the rails which is seri- 45 ously objectionable both because of the noise and wear on wheels and rails.

In efficiency, worm gearing when well designed has a substantial advantage over spur

and bevel gearing. Perhaps the most important advantage is the possibility of using 50 for such comparatively slow speed vehicles as street railway cars a high speed motor or a higher speed motor than those heretofore possible with a consequent reduction in size 55 and weight of the motor and a more efficient and economical operation thereof.

The use of a longitudinal flexible driving 60 shaft has special advantages in the operation of two pairs of wheels from a single motor, as illustrated. The shaft is arranged 65 along the central line of the truck. When the car enters a curve or other situation 70 where one rail is elevated, the front axle will be warped relatively to the rear axle, but the movement will take place around the central shaft and will be taken up at the point of engagement of the worm with its worm gear and the motor and driving mechanism will be practically unaffected by the warped position of the two axles.

Various modifications in the separate parts 75 of the mechanism and in the arrangement thereof may be made by those skilled in the art without departing from the invention as defined in the following claim.

What I claim is—

A railway car driving mechanism including in combination a high speed motor O, two pairs of traction wheels A, separately rotatable wheel shafts B turning said wheels, 80 said motor being located between the front pair and the rear pair of wheels and having a shaft R extending lengthwise of the car, a pair of flexible shafts S T extending lengthwise in opposite directions from the 85 ends of the motor shaft and connected thereto, a worm V engaged and driven by each of said flexible shafts, a worm gear X engaged by said worm and driven thereby at a greatly reduced speed and differential gearing transmitting the rotation of said worm gears X without change of speed to said wheel shafts B.

In witness whereof, I have hereunto signed my name.

CHARLES H. CALKINS.
